RAILWAY TRAFFIC CONTROLLING APPARATUS

Paul H. Cragg, Wilkinsburg, Pa., assignor to The Union Switch & Signal Company, Swissvale, Pa., a corporation of Pennsylvania

Application June 8, 1933, Serial No. 674,839

17 Claims. (Cl. 246—130)

My invention relates to railway traffic controlling apparatus, and has for an object the provision of apparatus controlled by a car for causing operation of a traffic controlling device when 5 a car passes over a given track section in less than a predetermined time interval.

I will describe three forms of apparatus embodying my invention, and will then point out the novel features thereof in claims.

10 In the accompanying drawings, Fig. 1 is a diagrammatic view of one form of apparatus embodying my invention for causing the operation of a railway switch when a car approaching the switch passes over a given track section in less 15 than a predetermined time interval. Fig. 2 is a diagrammatic view of a second form of apparatus embodying my invention for controlling the operation of a highway crossing signal located at the intersection of a highway with the stretch 20 of railway over which traffic normally moves in one direction. Fig. 3 is a diagrammatic view of apparatus for controlling the operation of a highway crossing signal located at the intersection of a highway and a stretch of single track railway, and which apparatus also embodies my invention.

In each of the several views like reference characters designate similar parts.

Referring to Fig. 1, the reference characters 20 and 3 designate the traffic rails of a stretch of railway which include a railway switch 4. The traffic rails are divided into three track sections, 1T, 2T and 3T by means of the usual insulated rail joints, the switch 4 being located in the section 3T. Each track section is provided with the customary track circuit including a source of current such as a battery 5 connected across the rails at one end of the section and a track relay R with an exponent corresponding to the section connected across the traffic rails at the opposite end of the section. It is to be noted that the track relay 1TR is normally energized over a stick circuit easily traced and which includes its own front contact 6. The pickup circuit for the relay 1TR extends from the rail 2 over wire 7 to a back contact 8 of the track relay 3TR and thence over wire 9 and the winding of the relay 1TR to the opposite rail 3.

As indicated by a dotted line, a motor M is 50 operatively connected with the switch 4 through the medium of a standard switch machine (not shown) to operate the switch to a normal position for directing a car to the track designated by the reference character 10A, or to operate the 55 switch to a reverse position for directing a car

to the track 10B. The operation of the motor M is governed by a switch controlling relay WR in a customary manner. With relay WR de-energized, the motor is provided with a circuit extending from the terminal B of a convenient 5 source of current such as a battery, not shown, over front contact 11 of the track relay 3TR, back contact 12 of relay WR, controller contact 14—15 operated by the motor and closed except when the switch 4 is moved to the full normal position, armature 13, back contact 16 of relay WR, and field winding 17 to the opposite terminal C of the current source. At such time as relay WR is energized in a manner to be later described, current flows from the terminal B of the 15 current source over front contact 11 of relay 3TR, front contact 18 of relay WR, armature 13, controller contact 15—19 operated by the motor and closed except when the switch 4 is moved to the full reverse position, front contact 20 of relay 20 WR, and field winding 17 to the opposite terminal C of the current source. The flow of current in armature 13 when relay WR is energized is such as to cause the motor M to rotate in a direction for operating the switch 4 to its reverse 25 position, whereas the flow of current in armature 13 when relay WR is deenergized is such as to cause the motor M to rotate in a direction for operating the switch 4 to its normal position. It follows that with relay WR deenergized the 30 switch 4 is set to direct a car to the track 10A, and with relay WR picked up the switch is set to direct a car to the track 10B.

Associated with the track section 1T is a time measuring equipment comprising a flasher relay 35 NF and a relay chain designated as a whole by the reference character CR. The two windings 21 and 22 of the flasher relay NF are normally energized serially as will be readily understood by an inspection of Fig. 1. The parts of the relay 40 are so proportioned that with the two windings serially energized, the armatures 23 and 24 remain in the position to which they were last moved. As will shortly appear, however, the control circuits for the relay NF are arranged in such 45 a manner that the armatures 23 and 24 normally occupy the position illustrated in the drawings. At such time as the winding 22 is short-circuited and winding 21 energized, the armatures 23 and 24 are shifted to the left-hand position, that is, 50 to the position opposite that illustrated in Fig. 1. At such time as winding 21 is short-circuited and the winding 22 energized the armatures 23 and 24 are shifted to the right-hand position, that is, 55 to the position illustrated in Fig. 1.

The operation of the flasher relay NF is governed jointly by the two track relays 1TR and 2TR to cause operation of the relay during the time a car is travelling through the track section 1T, and to stop the operation of the relay as the car passes into the section 2T. The track relay 1TR when shunted closes at its back contact 25 a shunt path around the winding 22 and which extends from the center connection 26 over right-hand contact 27 of armature 23, back contact 25, and front contact 64 of relay 2TR. Under this condition, the armatures 23 and 24 are shifted to the left whereupon armature 23 opens the above-traced shunt path around the winding 22 and closes at its left-hand contact 28 a shunt path around the winding 21. Winding 22 is now energized and the armatures 23 and 24 are shifted back to the right-hand position. It follows that as long as the track relay 1TR 20 remains down and the track relay 2TR is picked up, the relay NF is operated to alternately shift its armatures 23 and 24 from one side to the other. The parts of the relay NF are so proportioned and adjusted that the armatures 23 25 and 24 make substantially 30 cycles per minute, that is, they make a complete movement once every two seconds. The flasher relay NF may be any one of several types but a preferred type is that disclosed and claimed in the United States Letters Patent Reissue 17,252 to C. S. Snavely and W. B. Wells, for Electrical relays. I have found that a relay of this construction when connected in the manner shown in Fig. 1 has excellent voltage characteristics and a remarkably uniform 35 time for each operating cycle.

The relays 1R, 2R, 3R, 4R and 5R of the relay chain CR are each of the direct current neutral type constructed with a continuity transfer contact. For example, the armature 29 of the relay 1R engages the front or transfer contact 30 before that contact becomes disengaged from the back contact 31. For each operation of the flasher relay NF to one side or the other, a relay of the chain CR is picked up and then retained 45 energized over a stick circuit, disconnecting at the same time a control circuit to be later described, and closing at a front contact the pickup circuit for the next succeeding relay. Assuming the track relay 1TR to be shunted and the 50 flasher relay NF operated as described hereinbefore, the closing of the back contact 32 of relay 1TR makes possible a pickup circuit for the first relay 1R of the chain when the relay NF makes its first swing toward the left. This pickup circuit can be traced from the B terminal of the current source over back contact 32, wire 33, left-hand contact 34 of armature 24, back contact 31, transfer contact 30 and winding of the 55 relay 1R to the opposite terminal C of the current source. Relay 1R on picking up closes its stick circuit for shunting around the armature 24, and which includes terminal B of the current source, back contact 32, wire 33, armature 29, transfer contact 30, winding of relay 1R and the battery terminal C. With relay 1R picked up, the 60 next swing of armature 24 to the right completes the pickup circuit for the second relay 2R of the chain. This pickup circuit for relay 2R extends from battery terminal B over back contact 32, wire 33, right-hand contact 35 of armature 24, front contact 36 of relay 1R, back contact 37 of relay 2R, transfer contact 38, winding of relay 2R, and to the battery terminal C. Relay 2R once picked up is retained energized 65 by its stick circuit easily traced and which in-

cludes the back contact 32 of relay 1TR and its own armature 39. With the second relay 2R retained energized, the second swing of the armature 24 to the left completes the pickup circuit for the third relay 3R of the chain, and which includes battery terminal B, back contact 32, wire 33, left-hand contact 34, front contact 40 of relay 2R, back contact 41 of relay 3R, transfer contact 42 and winding of relay 3R and the C terminal of the current source. As soon as relay 3R 10 has picked up, it is retained energized by the closing of its stick circuit which includes its own armature 43, and thus the second swing of armature 24 to the right closes the pickup circuit for the fourth relay 4R of the chain. This pickup circuit for relay 4R extends from the battery terminal B over back contact 32, wire 33, right-hand contact 35, front contact 44 of relay 3R, back contact 45 of relay 4R, transfer contact 46, and winding of relay 4R to the opposite battery 20 terminal C. Relay 4R, when picked up, is retained energized by its stick circuit which includes its own armature 47. With relay 4R picked up to close its front contact 47 the next swing of armature 24 to the left completes a 25 pickup circuit for the fifth relay 5R of the chain as will be readily understood by an inspection of Fig. 1 and which pickup circuit includes its own back contact 48 and transfer contact 49. Relay 5R is then retained energized over its stick 30 circuit which includes its own armature 50. It follows that armature 24 is operated to make one complete cycle in a predetermined time interval and that the complete time of operation is summed up by the number of relays of the chain 35 picked up. Although I have shown only five relays for the chain CR, it is clear that any number of relays may be added to the chain, and pick up and stick circuits provided for each relay whereby any desired time of operation for the relay NF 40 may be measured. It is to be noted that the relays of the chain CR are not dropped as they are passed as is the customary manner for relay time chains, but all preceding relays to the one last picked up are retained energized by 45 individual stick circuits.

The relay chain CR controls the switch controlling relay WR in the following manner: At such time as the track relay 2TR is shunted to close its back contact 51 a circuit is completed 50 from the terminal B of the current source over back contact 51, wire 52, back contacts 53, 54, 55, 56 and 57 of the relays 1R, 2R, 3R, 4R and 5R, respectively, in parallel, and thence over line wire 58 and the winding of relay WR to the terminal C of the current source and relay WR is 55 picked up. Relay WR is provided with a stick circuit easily traced and which includes a front contact 59 of the track relay 3TR and its own front contact 60.

A car entering the track section 1T of Fig. 1 will drop the track relay 1TR and start operation of the flasher relay NF to pick up successively the relays of the chain CR. If the speed of the car is slow enough all the relays of the chain 65 CR will have been picked up before the car reaches the track section 2T, and the switch controlling relay WR will remain deenergized when the car enters section 2T due to the fact that all the back contacts 53, 54, 55, 56 and 57 70 will be open. Under this condition the switch 4 will not be moved and the car will advance over the switch to the track 10A. If the speed of the car is too high so that it travels the track section 1T before all the relays of the chain are 75

picked up, the switch controlling relay WR will become energized as soon as the car enters the section 2T and shunts the track relay 2TR due to the fact that the pickup circuit for the relay 1WR will be closed over the back contacts of the relays of the chain remaining deenergized. Under this condition, the motor M will be operated to move the switch to its reverse position and the car will advance over the switch to the track 10B. By introduction of manually controlled switches K1 and K2 in the pickup circuit for the relay WR the time of operating switch 4 may be varied. For example, if the switch K1 is opened a car moving slow enough in the section 1T to permit the two relays 1R and 2R to be picked up will cause the relay WR to remain deenergized and the switch 4 will not be operated. If the switch K1 is closed and switch K2 is opened then a car moving slow enough in section 1T to permit the first four relays of the chain to be picked up will prevent the relay WR from being energized and the switch 4 will not be operated.

It will be noted that once relay 1TR is shunted, it can be reenergized only after a car has advanced into the section 3T and shunted the track relay 3TR to close the back contact 8 in the pickup circuit for relay 1TR. The stick circuits for the energized relays of the chain will be supplied with energy as long as the relay 1TR remains down and hence, the energizing circuit for the relay WR if closed will remain intact while the car occupies the section 2T. As the car passes from section 2T into the section 3T, the shunting of the track relay 3TR will open the front contact 11 in the motor operating circuit and hence if relay WR has been picked up to reverse the switch 4, the motor M will not be operated to move the switch as long as the car remains in the section 3T. When the car vacates the section 3T, the relay WR will be deenergized and the motor M will be operated to restore the switch to its normal position automatically. To sum up the operation of the apparatus of Fig. 1, a car travelling through a given track section 1T at too high a speed so that it reaches the outgoing end of the section in less than a predetermined time interval will cause the switch 4 to be automatically set in a position to advance the car to the track 10B. Should a car move slow enough as it travels the predetermined track section 1T so that it consumes more than a predetermined time interval before it reaches the outgoing end of the section, the switch 4 will remain in its normal position and the car will move to the track 10A. At such time as the switch has been reversed to move the car to the track 10B, the vacating of the track section 3T causes the apparatus to automatically restore the switch to its normal position.

Many applications for the apparatus of Fig. 1 will naturally suggest themselves to those skilled in the art. For example, at hump or scale tracks, a car moving on the scale track (section 1T) at too high a speed to permit weighing and classification of the car will automatically cause switch 4 to be reversed to direct that car to an emergency track where it can be later brought back and again pushed over the scales. Cars moving over the scales slow enough to be properly weighed and classified will pass over the switch 4 in its normal position and move to the usual classification yard (track 10A).

Referring to Fig. 2, the same principle of control is applied to the operation of a highway crossing signal. The traffic rails 2 and 3 of a

stretch of railway over which traffic normally moves in the direction indicated by an arrow are intersected by a highway indicated by the reference character H. At the intersection there is located a highway crossing signal S. This signal S may be of any of the usual type of highway crossing signals and is here illustrated as an audible signal in the form of an electric bell. It will be understood, however, that my invention is not limited to any specific form of highway crossing signal but may be any standard type in general use. The immediate operation of the signal S is governed by a controlling relay HR which when energized to close its front contact 63 completes a simple operating circuit 15 for the signal S.

The traffic rails 2 and 3 of Fig. 2 are divided by the usual insulated rail joints into five consecutive track sections designated by the reference characters 1T, 2T, 3T, 4T and 5T and which 20 sections are traversed in the order named by a train as it approaches the highway when moving in the normal direction of traffic. Each track section is provided with the usual track circuit comprising a track battery 5 and a track relay 25 R with an exponent corresponding to the track section. The control of the track relay 2TR departs from the usual custom in that it is normally held energized over a stick circuit that includes its own front contact 61, and is provided 30 with a pickup circuit that includes the front contact 62 of the track relay 1TR as will be readily understood by an inspection of Fig. 2. The function of this control provided for the relay 2TR will appear when the operation of the apparatus 35 of Fig. 2 is described.

Associated with the track section 1T is a time measuring equipment comprising a flasher relay NF and a relay chain CR. The flasher relay NF is preferably similar to the flasher relay of Fig. 1 40 and is normally inactive. At such time as the track relay 1TR is shunted and the track relay 2TR remains picked up, a shunt path is formed around the winding 22 of relay NF, and which includes the back contact 25 of relay 1TR and a 45 front contact 76 of the relay 2TR. It follows that as long as the track section 1T is occupied and the track section 2T is unoccupied, the flasher relay NF is active to alternately shift the armature 24 between the right-hand contact 35 and 50 the left-hand contact 34 at the rate of thirty times per minute. It will be understood, of course, that my invention is not limited to any specific rate of operation of the flasher relay and its rate may be made to suit specific locations. 55 The alternate operation of the armature 24 serves to successively close the pickup circuits for the successive relays of the chain CR in the same manner as described for Fig. 1 and it is deemed unnecessary to repeat this operation in detail. It is to be noted that the stick circuit for each of the relays of the chain of Fig. 2 receives energy over a front contact 65 of the track relay 5TR and a line wire 66. For example, the stick circuit for the relay 1R extends from the B battery terminal over front contact 65, line wire 66, armature 29 of relay 1R, transfer contact 30, winding of relay 1R and to the opposite battery terminal C. Consequently, the time consumed by a train in travelling the first track section 1T 70 is summed up by the number of relays of the chain CR energized at the time the train enters the section 2T and stops the operation of the flasher relay NF. The relays of the chain picked up are retained energized over their stick cir- 75

cuits until the train advances to the last track section 5T and shunts the track relay 5TR.

The signal controlling relay HR is provided with a plurality of different energizing circuits. A first energizing circuit for relay HR can be traced from the B terminal of the current source over back contact 77 of relay 2TR, wire 67, back contact 68 of relay 3R, line wire 69 and winding of relay HR to the opposite terminal C of the current source. A second energizing circuit extends from the B battery terminal over back contact 70 of the relay 3TR, wire 71, back contact 72 of relay 4R and thence as before traced. A third energizing circuit extends from the B terminal of the current source over back contact 73 of the relay 4TR, wire 74, back contact 75 of relay 5R, and thence as before traced. In addition to these three energizing circuits already traced and each of which is controlled by a relay of the chain, the relay HR may be energized by current supplied over the back contact 119 of the track relay 5TR.

Assuming all the track sections of Fig. 2 to be unoccupied and that a train moving in the normal direction of traffic is approaching the highway H at a relatively high rate of speed, the train first enters the track section 1T and shunts the track relay 1TR to start the operation of the flasher relay NF. While the train occupies the section 1T and before it enters the section 2T, the flasher relay NF is active to successively energize the relays of the chain in step with the alternate movement of the armature 26. The shunting of the track relay 2TR opens the operating circuit for the relay NF and operation of that relay is stopped with the armature 24 assuming its normal right-hand position. The time required for this train to travel the section 1T is summed up by the number of relays of the chain energized, and hence, if the speed is relatively high so that the relay 3R is not picked up before the train enters the section 2T the first energizing circuit for the relay HR is completed as soon as the relay 2TR is shunted. It follows that for a relatively high speed train the highway crossing signal S is operated to warn highway users all the time the train is advancing through sections 2T, 3T, 4T and 5T. Next, I shall assume that the train advances through the section 1T at a somewhat lower speed, and that the relays 1R, 2R and 3R are picked up before the train enters the section 2T. Under this condition, the shunting of the track relay 2TR does not complete the first energizing circuit for relay HR due to the fact that the back contact 68 of relay 3R is open, and hence the signal S is not operated during the time the train occupies the section 2T. When this train has advanced to the section 3T, the shunting of the track relay 3TR completes the second energizing circuit for the relay HR inasmuch as the back contact 72 of relay 4R is closed. It follows that for this train travelling at a somewhat lower speed, the signal S is operated during the time the train occupies the sections 3T, 4T and 5T. Again, let us assume that the train is travelling at only a medium speed and the time it consumes in the section 1T is sufficient to permit the first four relays of the chain to pick up before the train shunts the track relay 2TR. This time neither the first energizing circuit for the relay HR, nor the second energizing circuit is closed due to the fact that the back contacts 68 and 72 of relays 3R and 4R, respectively, are open. When this train advances to the section 4T and shunts the track relay 4TR the

third energizing circuit for relay HR is completed and hence the signal S is operated during the time this train travelling at a medium speed occupies the two track sections 4T and 5T. In the event the train approaching the intersection is travelling at a relatively low speed and the time it consumes in the first section 1T is sufficient to permit the complete chain of relays to be picked up, neither the first, second nor third energizing circuit for the relay HR is closed, and hence that relay is not energized and the signal S is not operated until the train enters the section 5T.

It was previously pointed out that the stick circuits for the relays of the chain CR receive current over the front contact 65 of the track relay 5TR and, consequently, as soon as a train enters the final section 5T, all the energized relays of the chain are released and restored to their normal deenergized position.

It is clear that knowing the maximum speed for trains over the stretch of track of Fig. 2, proper lengths for the various track sections can be selected so that the distance from the intersection at which the warning signal is set into operation will be so varied in accordance with the speed of the train that approximately a uniform period of warning will be provided for all trains. It will be understood, of course, that the length of the track section 1T and the time equipment are so proportioned and adjusted as to select the proper point at which to start operation of the highway signal S. The controlling relay HR of Fig. 2 may be of the interlocking type in which the first operating portion energized prevents full operation of the second energized portion, and the operating circuit of signal S controlled in such a manner as to avoid operation of the signal when the stretch of railway is traversed by a train moving against the normal direction of traffic. A train moving against traffic will shunt the track relay 2TR before the track relay 1TR is shunted and relay 2TR will not be reenergized until the train vacates the section 1T and relay 1TR is picked up. Relay 2TR being held down during the time the train moving against traffic occupies the section 1T, the flasher relay NF remains inactive as this train moves away from the intersection.

Referring to Fig. 3, the traffic rails 2 and 3 of a stretch of single track railway are intersected by a highway H at which there is located a highway crossing signal S. The traffic rails to the left of the highway H are divided into the track sections 1T, 2T, 3T, 4T and 5T in a manner similar to that of Fig. 2. The traffic rails to the right of the highway H are divided into a similar set of track sections as designated by the reference characters 6T, 7T, 8T, 9T and 10T.

In order to simplify the description I shall refer to a train moving from the left to the right in Fig. 3 as an eastbound train and a train moving from the right to the left as a westbound train. For clarity certain of the contacts of the relays of the chain CR are located in Fig. 3 remote from the winding of the relay. In all such instances the reference character of the relay is located just above the contact and the contact is further identified by a specific reference character.

The immediate control of the signal S is obtained by an interlocking relay HR1, the two windings 73 and 74 of which are controlled by traffic to the left and right of the highway H, respectively, as will shortly appear. A timing equipment comprising a flasher relay NF and

a relay chain CR similar to the corresponding equipment for Figs. 1 and 2 is controlled by both the measuring track sections 1T and 10T. At such time as the track relay 1TR is down and the track relay 2TR remains picked up, a shunt path is formed around the winding 22 of relay NF from the B terminal of the current source over front contact 76 of relay 2TR, back contact 25 of relay 1TR, line wire 89, front contact 81 of interlocking relay HR1, right-hand contact of armature 23 and to the center winding connection of the relay NF. Again, at such time as the track relay 10TR is down and the track relay 9TR remains picked up a shunt path is formed around the winding 22 from the B battery terminal over front contact 82 of relay 9TR, back contact 83 of relay 10TR, line wire 84, front contact 85 of interlocking relay HR1 and thence as before traced. It follows that the flasher relay NF is operated during the interval an eastbound train is passing over the track section 1T, and also during the interval a westbound train is passing over the track section 10T. A westbound train occupying the section 1T is not effective to operate relay NF due to the fact that the winding 78 of the interlocking relay HR1 is not energized at this time to close the front contact 81 as will appear hereinafter. Due to the fact that the winding 79 of the interlocking relay HR1 is held deenergized while an eastbound train occupies the section 10T, that train is ineffective to operate the flasher relay NF. Operation of the flasher relay NF is effective to pick up the successive relays of the chain CR in a manner similar to that described for Fig. 1. For example, with an eastbound train in the section 1T the first swing of the armature 24 to the left completes the pickup circuit for relay 1R, and which circuit includes a front contact 86 of relay 2TR, back contact 87 of relay 1TR, line wire 88, left-hand contact of armature 24, back contact 31 of relay 1R, transfer contact 30, and winding of relay 1R to the opposite terminal of the current source. With relay 1R picked up, it is held energized by its stick circuit and 89 of the track relay 6TR, front contact 90 of the track relay 5TR, and its own armature 29 as will be readily understood by an inspection of Fig. 3. From this point on, the successive operation of the armature 24 will successively energize the relays of the chain over the circuits just traced with the result that the time required for an eastbound train to travel the track section 1T is summed up by the number of relays of the chain energized. In a similar manner, the relays of the chain are counted off as a westbound train occupies the section 10T. In this latter case, the pickup circuit for energizing the relays of the chain include the front contact 91 of relay 9TR, back contact 92 of relay 10TR, line wire 93 to the armature 24 and thence as before traced as will be readily understood from Fig. 3. The stick circuit for retaining the relays energized is the same for the westbound train as for the eastbound train. It follows that the timing equipment comprising the relay NF and the relay chain CR functions for an eastbound train approaching the highway H to determine the time that train consumes in passing over the section 1T, and functions in a like manner to determine the time a westbound train approaching the highway H consumes in passing over the section 10T.

Assuming all the track sections to be unoccupied and that an eastbound train is approaching the intersection, this train will cause the timing equipment to measure the time it consumes in passing over the section 1T. In the event the train is travelling at a relatively high speed and chain relay 3R is not picked up before the train enters the section 2T, the signal S is set into operation at once. The releasing of the track relay 2TR opens the holding circuit for the winding 78 of the interlocking relay HR1, and the releasing of that winding closes at the back contact 118 the operating circuit for the signal S. The holding circuit for winding 78 normally extends from the terminal B of the current source over front contacts 94, 95 and 96 of the track relays 2TR, 3TR and 4TR, respectively, front contact 97 controlled by winding 78, front contact 98 controlled by relay 5TR and winding 78 to the opposite terminal C of the current source. It follows that winding 78 will remain deenergized and the signal S operated while this eastbound train passes over the sections 2T, 3T, 4T and 5T. As soon as the rear of the train vacates the section 5T, the winding 78 is reenergized by current supplied over a pickup circuit that includes the front contacts 94, 95 and 96 and thence extends over line wire 101, front contact 100 of relay 1TR, line wire 99, front contact 98 of relay 5TR and winding 78 to the C battery terminal. Although the winding 79 of the interlocking relay will be deenergized while the eastbound train moves away from the highway H through the sections shown at the right of the highway, the interlocking feature of relay HR1 will prevent the closing of the back contact 117 controlled by winding 79 and signal S will not be operated. Assuming a somewhat lower speed for the eastbound train as it approaches the highway intersection and that the chain relay 3R is picked up before the track relay 2TR is shunted, the winding 78 will receive current from the B terminal of the current source over front contact 110 of relay 3R and thence over the holding circuit above traced. Under this condition, the winding 78 will remain energized until the eastbound train enters the section 3T and track relay 3TR is released. The control of the interlocking relay HR1 as this train moves away from the highway H will be the same as for the first eastbound train. In the event the eastbound train is moving only at a medium speed and chain relay 4R is picked up while the train is passing over section 1T, the winding 78 will receive current from the B terminal of the current source over front contacts 110 and 111 of relays 3R and 4R, respectively, and the holding circuit described above. Consequently, the signal S is operated for this eastbound train travelling at medium speed only during the time it occupies the sections 4T and 5T. Again, if the eastbound train is travelling at a relatively low speed and the five relays of the chain CR are all picked up, the winding 78 receives current from the B terminal of the current source over front contacts 110, 111 and 112 of the relay chain and the holding circuit described above with the result that the signal S will be operated only while the train occupies the track section 5T.

Winding 79 of the relay HR1 is provided with a normal energizing stick circuit extending from B battery terminal over front contacts 102, 103 and 104 of track relays 9TR, 8TR and 7TR, respectively, its own front contact 105, front contact 106 of track relay 6TR and winding 79 to the C battery terminal. The pickup circuit for 75

winding 79 extends from B battery terminal over the same circuit up to front contact 104 and thence over line wire 109, front contact 108 of relay 10TR, line wire 107, front contact 106 and winding 79 to the C battery terminal. It is clear therefore that the apparatus of Fig. 3 will function to control the normal stick circuit for winding 79 in response to westbound trains in the same manner as described for eastbound trains controlling the winding 78 of relay HR1. The front contacts 113, 114 and 115 of the relays 3R, 4R and 5R, respectively, determine the track section at which the winding 79 becomes deenergized to close the operating circuit for the signal S. Although the winding 78 will be deenergized while a westbound train moves away from the highway H, the interlocking feature of the relay HR1 will prevent the closing of the back contact 116 controlled by the winding 78.

The utility of railway traffic controlling apparatus such as here disclosed is that it provides a flexible time measuring device which will remain accurate notwithstanding a relatively large variation of voltage of the current source, and which will automatically function to operate a mechanism in response to a car or train passing over a given track section at a speed above a given value.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In combination, a first and a second track section to be successively traversed by a car, a flasher relay, means to operate said relay as a car travels said first track section, a chain of relays normally deenergized, means to successively energize the relays of said chain in step with the operation of said flasher relay, a stick circuit for each relay of the chain adapted to retain its relay energized when once picked up, an operating mechanism normally inactive, control means rendered effective as the car enters said second track section to operate said mechanism, and means governed by the relay chain to render the control means ineffective when a predetermined number of relays of said chain are energized.

2. In combination, a first and a second track section to be successively traversed by a car, a flasher relay, means to operate said relay as a car travels said first track section, a chain of relays normally deenergized, means to successively energize the relays of said chain in step with the operation of said flasher relay, a stick circuit for each relay of the chain adapted to retain its relay energized when once picked up, an operating mechanism normally inactive, means governed by said relay chain rendered effective as the car enters said second track section to operate said mechanism unless a predetermined number of said relays are energized, and means governed by said car for subsequently opening said stick circuits.

3. In combination, an operating mechanism located at one point along a railway and normally inactive, a flasher relay, means to set said flasher relay into operation as a car passes a first given point in approaching said one point, a chain of relays normally deenergized, means to successively energize the relays of said chain in step

with the operation of said flasher relay, means to stop the operation of the flasher relay as the car passes a second point in approaching said one point, control means effective as the car passes said second given point to render the operating mechanism active, and means governed by the relay chain to render the control means ineffective when a predetermined number of the relays of said chain are energized.

4. In combination, an operating mechanism located at one point along a railway and normally inactive, a flasher relay, means to set said flasher relay into operation as a car passes a first given point as it approaches said one point, a chain of relays normally deenergized, means to successively energize the relays of said chain in step with the operation of said flasher relay, a stick circuit for each relay of the chain, means to stop the operation of the flasher relay as the car passes a second given point in approaching said one point, and means governed by said relay chain effective as the car passes said second given point to render the operating mechanism active unless a predetermined number of the relays of said chain are energized.

5. In combination, an operating mechanism located at one point along a railway and normally inactive, a flasher relay, means to set said flasher relay into operation as a car passes a first given point in approaching said one point, a chain of relays normally deenergized, means to successively energize the relays of said chain in step with the operation of said flasher relay, means to stop the operation of the flasher relay as the car passes a second point in approaching said one point, control means effective as the car passes said second given point to render the operating mechanism active unless a predetermined number of the relays of said chain are energized.

6. In combination, an operating mechanism located at one point along a railway and normally inactive, a first and a second track section to be successively traversed as a car approaches said one point, a first track relay for said first section and a second track relay for said second track section, a flasher relay, an operating circuit for said flasher relay including a front contact of the second track relay and a back contact of the first track relay, a chain of relays normally deenergized, a pickup circuit for each relay of said chain and each including an armature of the flasher relay and a front contact of the preceding relay of the chain whereby said relays are energized successively in step with the alternate operation of said armature, a stick circuit for each relay to retain its relay energized irrespective of said flasher relay, and an operating circuit for said operating mechanism including a back contact of a given relay of said chain and a back contact of the second track relay whereby said mechanism is rendered active in response to a car entering the second track section unless said given relay of said chain is picked up.

7. In combination, an operating mechanism located at one point along a railway and normally inactive, a first and a second track section to be successively traversed by a car approaching said one point, a first track relay for said first section and a second track relay for said second section, a flasher relay having a predetermined frequency of operation, an operating circuit including a front contact of the second track relay and a back contact of the first track relay for op-

- erating said flasher relay, a chain of relays normally deenergized, a pickup circuit for each relay of the chain and each including an armature of the flasher relay and a front contact of the preceding relay of the chain whereby said relays are energized successively in step with the alternate operation of said armature, a stick circuit for each relay to retain its relay energized irrespective of said flasher relay, and an operating circuit including a back contact of the second track relay and a back contact of the final relay of said chain for the operating mechanism whereby said mechanism is rendered active when a car passes over the first track section at too high a speed.
8. In combination, a railway switch having a first and a second position and normally occupying its first position, operating means for moving the switch, a first and a second track section traversed by a car in approaching the switch, a flasher relay, means for operating said relay as a car travels the first track section, a chain of relays normally deenergized, means to successively energize the relays of the chain in step with the operation of said flasher relay, control means governed by the relay chain effective to control the operating means to move the switch as the car enters said second track section, and means governed by the relay chain to render the control means ineffective when a predetermined number of the relays of said chain are energized.
9. In combination, a railway switch having a first and a second position and normally occupying its first position, operating means for moving the switch, a first and a second track section traversed by a car in approaching the switch, a flasher relay, means for operating said relay as a car travels the first track section, a chain of relays normally deenergized, means to successively energize the relays of the chain in step with the operation of said flasher relay, control means effective as a car enters said second track section to control the operating means to move the switch to the second position, and means governed by the relay chain effective when and only when a predetermined number of relays of said chain are energized to render said control means ineffective.
10. In combination, a stretch of railway track intersected by a highway, a highway crossing signal located at the intersection, controlling means for setting the signal into operation when a train approaching the intersection reaches a fixed point, a flasher relay, means for operating said relay as a train approaches said fixed point, a normally deenergized relay chain, means for energizing the relays of said chain successively in step with the operation of said flasher relay, a stick circuit for each relay of the chain, means controlled by said relay chain for rendering the controlling means ineffective when a predetermined number of relays are energized before the train reaches said fixed point, and means for annulling the control of said relay chain when the train reaches a second fixed point nearer to the intersection.
11. In combination, a stretch of railway track intersected by a highway, a highway crossing signal located at the intersection; a first, a second and a third fixed point which a train successively passes as it approaches the intersection; controlling means for setting the signal into operation when a train reaches said first fixed point, a flasher relay, means for operating said relay as a train approaches said first fixed point, a normally deenergized relay chain, means for energizing the relays of said chain successively in step with the operation of the flasher relay, a stick circuit for each relay of the chain, means controlled by said relay chain for rendering the controlling means ineffective when a predetermined number of relays are picked up before the train reaches said first fixed point, and means for annulling the control of said relay chain when the train reaches either the second or the third fixed point depending upon the number of relays of the chain energized.
12. In combination, a stretch of railway track intersected by a highway, a highway crossing signal located at the intersection; a first, a second and a third track section which a train successively travels as it approaches the intersection; a flasher relay, means for operating said relay as a train travels the first track section, a chain of relays normally deenergized, means for energizing the relays of the chain successively in step with the operation of said flasher relay, a stick circuit for each relay of the chain for retaining its relay energized irrespective of the flasher relay, controlling means for setting said signal into operation when a train enters said second track section, means controlled by said relay chain in response to a predetermined number of said relays being held energized to render said controlling means ineffective, and means responsive to the train entering the third track section for annulling the control of said relay chain.
13. In combination, a stretch of single track railway intersected by a highway, a highway crossing signal located at the intersection, an interlocking relay, a circuit controlled by said relay for operating the signal, a first and a second track section travelled in the order named by an eastbound train approaching the intersection, a third and a fourth track section travelled in the order named by a westbound train approaching the intersection, a flasher relay, means to operate the flasher relay in response to an eastbound train passing over the first track section and in response to a westbound train passing over the third track section, a relay chain normally deenergized, means to energize the relays of said chain successively in step with the operation of said flasher relay, and means governed jointly by said relay chain and the second and the fourth track sections for controlling said interlocking relay.
14. In combination, a stretch of single track railway intersected by a highway, a highway crossing signal located at the intersection, an interlocking relay having a first and a second magnet, a circuit controlled by said relay for operating the signal, a plurality of consecutive eastbound track sections to be travelled by an eastbound train approaching the intersection, a plurality of consecutive westbound track sections to be travelled by a westbound train approaching the intersection, a flasher relay, means to operate the flasher relay as an eastbound train passes over the most remote eastbound section and as a westbound train passes over the most remote westbound section, a relay chain normally deenergized, means to energize the relays of the chain successively in step with the operation of the flasher relay, means controlled by the energized relays of the chain in cooperation with the eastbound track sections to govern the first magnet of the interlocking relay, said control being effective to select the section at which to start operation of the signal in accordance with the speed of the eastbound train so as to give approximately a like period of operation for all trains, and

- means controlled by the energized relays of the chain in cooperation with the westbound track sections to govern the second magnet of the interlocking relay, said control being effective to
5. select the section at which to start operation of the signal in accordance with the speed of the westbound train so as to give approximately a like period of operation for all trains.
  15. In combination, a stretch of single track
  10. railway intersected by a highway, a highway crossing signal located at the intersection, an interlocking relay having a first and a second magnet, a circuit controlled by said relay for operating the signal, a plurality of consecutive eastbound track sections to be travelled by an eastbound train approaching the intersection, a time measuring device normally inactive, operating means responsive to an eastbound train passing over the most remote eastbound track section and to a westbound train passing over the most remote westbound track section to render the time measuring device active, a first control means governed by said device in cooperation with the eastbound sections to control the first magnet of the interlocking relay for governing the operation of the signal in accordance with the speed of eastbound trains, a second control means governed by said device in cooperation with the westbound sections to control the second magnet of the interlocking relay for governing the operation of the signal

in accordance with the speed of westbound trains, and means controlled by the interlocking relay for rendering the operating means ineffective as a westbound train passes over the eastbound sections and as an eastbound train passes over the westbound sections.

5

16. In combination, a section of railway track, a flasher relay, an operating circuit controlled by a car to operate said relay while the car traverses said section, a chain of relays normally deenergized, means including an armature of said flasher relay to successively energize the relays of said chain in response to operation of said flasher relay, a stick circuit for each relay of the chain to retain that relay energized irrespective of said flasher relay, a traffic governing mechanism normally inactive, and circuit means controlled by the relay chain to effect operation of said mechanism in accordance with the number of relays picked up in response to the car traversing said section.

17. In combination, a railway switch having a first and a second position, operating means for moving the switch, a flasher relay, means controlled by a car for operating said relay as the car travels a given track section in approaching the switch, a chain of relays normally deenergized, means to successively energize the relays of the chain in response to operation of the flasher relay, and control means controlled jointly by the car when it has traveled said section and by said relay chain for governing the operating means.

PAUL H. CRAGO.
